[57] CLAIM

The ornamental design for a log handling device, as
shown and described.

DESCRIPTION

FIG. 1 is a perspective view of a log handling device
showing my new design;

FIG. 2 is a front view thereof;

FIG. 3 is a right side elevational view thereof;

FIG. 4 is a left side elevational view thereof;

FIG. 5 is a back elevational view thereof;

FIG. 6 is a view in top plan thereof; and

FIG. 7 is a bottom plan view thereof.

FIG. 1

FIG. 2

FIG. 3

FIG. 4

FIG. 5

FIG. 6

FIG. 7
